CLAIM

The ornamental design for a mammography equipment, as shown and described.

DESCRIPTION

FIG. 1 is a top, front and right side perspective view of a mammography equipment showing my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof.

1 Claim, 6 Drawing Sheets
